UNITED STATES PATENT OFFICE.

OTTO A. MOSES, OF NEW YORK, N. Y.

VOLTAIC-ARC LAMP.

SPECIFICATION forming part of Letters Patent No. 293,495, dated February 12, 1884.

Application filed April 20, 1883. (No model.)

To all whom it may concern:

Be it known that I, OTTO A. MOSES, of New York city, in the county and State of New York, have invented a new and useful Improvement 5 in Voltaic-Arc Lamps, of which the following is a specification.

The object of my invention is to enable the light of the voltaic arc to be employed in producing signals for transmitting intelligence in 10 maritime and military operations and for other purposes. The signals are produced by variations in and partial or entire cessations of the light of the arc caused by variations in the action of the feeding or regulating mechanism.

15 In carrying out my invention I prefer to provide the arc-lamp with two circuits, one including the carbons and the electro-magnetic devices which operate the regulating mechanism, (which may be termed the "signaling- 20 circuit,") the other (which I term the "incandescent circuit") including the carbons alone. When the latter circuit is closed, the carbons remain together and are heated to incandescence. On breaking this circuit and closing 25 the other, the carbons are separated, and by continuing to open and close this signaling-circuit at intervals flashes of light are produced.

In operating the apparatus, while the signaling-circuit is opened and closed, the incandescent circuit is constantly closed, so that the 30 carbons remain incandescent and do not become cooled, and are therefore always ready to produce the signal-flashes at once, and, in addition, the position of the light can be constantly observed in the intervals of darkness 35 between the signal-flashes by the incandescent glow, which is readily distinguishable from the intense and penetrating glare of the arc.

A modification of the arrangement described 40 consists in the use of two sets of solenoid or magnet coils, acting oppositely upon the movable carbon-carrier, and each included in a circuit, which also includes the carbons and arc. The double action produced by opening or 45 closing these circuits may give a quicker and more reliable action to the mechanism. The circuit of the downwardly-acting solenoid should be of greater resistance than that of the other, as in moving downwardly the action of 50 the magnet or solenoid is assisted by gravity.

In this case, also, a circuit should be provided including the arc alone without the regulating mechanism to keep the carbons constantly heated. In both forms of the lamp suitable dash-pots are provided, as usual, to retard and 55 regulate the movement of the carbon-carrier.

My invention is illustrated in the annexed drawings, in which Figure 1 is a diagram illustrating the first-described form of my invention; Fig. 2, a diagram illustrating the form 60 in which oppositely-acting solenoid or magnet coils are employed, and Fig. 3 a view of the lamp used in this latter form.

In Fig. 1, *a* *a'* represent, respectively, the upper and lower carbons, and *b* represents the 65 upper-carbon carrier, whose movement is regulated by the magnet or solenoid *c*. *A* represents a battery or other source of electric energy. A circuit-wire, 1, runs to a key, *d*, which, when depressed, makes contact with the contact-point *e*. A circuit-wire, 2, runs to key *d'*, which makes contact at *e'*. From contact *e* a wire, 3, forming the incandescent circuit, runs, which is connected directly with the carbon-carrier *b*. From contact *e'* the wire 4, which 75 is the signaling-circuit, runs to the magnet or solenoid coil *c*. A suitable resistance, *f*, should be included in the incandescent circuit, to prevent a short circuit when the carbons are together. 80

In operating this apparatus, the key *d* is kept constantly depressed, whereby the incandescent circuit is constantly maintained. When the key *d'* is depressed, the signaling-circuit is closed, and the magnet or solenoid *c* raises the 85 upper carbon and forms the arc. On raising the key *d'*, the carbon-carrier drops and the arc is destroyed. By varying the intervals of depression, and raising of the key, flashes of light and intervals of comparative darkness of 90 different lengths are produced, whereby signals of a prearranged code may be rendered visible at a distance. The Morse telegraphic signals can readily be produced in this way. A resistance, preferably an incandescent electric 95 lamp, *g*, should be placed in a shunt around each circuit-breaking point, to diminish the spark at such points.

In Figs. 2 and 3 the arrangement in which 100 oppositely-wound coils act on the carbon-car-

rier is illustrated. It is to be understood that Fig. 2 is merely a diagram intended to illustrate clearly the circuits and connections, while the construction of the regulator is shown in Fig. 3. Oppositely-wound coils *h* and *h'* act reversely on the carbon-carrier *b*. Coils *h* are in a circuit, 1 5, from the source of energy, and coils *h'* in a circuit, 1 6. Both these circuits include also the carbons *a a'*, while an incandescent circuit is also provided including said carbons alone. The coils *h* act to lift the carbon-carrier, while coils *h'* tend to depress it. The resistance *i* in the circuit including the upwardly-acting coils is greater than that in the downward circuit, as previously explained. When the circuit 1 5 is closed and the circuit 1 6 opened, the upper carbon is lifted, and when 1 6 is closed and 1 5 opened, it is quickly depressed. Circuit 1 7 would be constantly closed.

The regulator which I prefer to use is substantially such as is shown in several prior applications made by me for Letters Patent, and is illustrated in Fig. 3 of the drawings.

25 C is the carbon-carrying tube containing the viscous liquid D, and inclosing the divided core or armature E. The controlling magnet or solenoid which surrounds the tube consists in this case of two sets of coils wound oppositely, one, *h*, upon the other, *h'*, so that they act opposingly upon the tube, the divided core or armature E, and the intensifier F, which is

placed without the tube. The coils may be wound one above the other, or in any suitable manner, so that they can both act upon the 35 regulating mechanism.

What I claim is—

1. A voltaic-arc lamp having two paths for the current, one through the regulating mechanism and the carbons, the other through the 40 carbons alone, substantially as set forth.

2. The combination, with a voltaic-arc lamp, of a circuit or circuits including the regulating mechanism and the carbons, a circuit including the carbons alone, and means for opening 45 and closing either or both of said circuits, substantially as set forth.

3. The combination, with an arc-lamp, of electro-magnetic devices acting oppositely upon the movable carbon-carrier, and means for 50 closing circuit to either of such devices, substantially as set forth.

4. The combination, with an arc-lamp, of the oppositely-acting electro-magnetic devices, a circuit energizing each of such devices, and 55 also the carbons, a circuit including the carbons alone, and a circuit-controller for each of said circuits, substantially as set forth.

This specification signed and witnessed this 6th day of March, 1883.

OTTO A. MOSES.
